(57) **CLAIM**

I claim the ornamental design for a flexible cover for holding mink pelts on a pelt device, as shown and described.

DESCRIPTION

FIG. 1 is a front view of the flexible cover for holding mink pelts on a pelt device, showing my new design;

FIG. 2 is a perspective view thereof;

FIG. 3 is a right side view thereof, the left side being a mirror image thereof; and,

FIG. 4 is an end view thereof.
